(57) **CLAIM**

The ornamental design for a “plate,” as shown and described.

DESCRIPTION

FIG. 1 is a top plan view of a plate;

FIG. 2 is a side elevational view (all side views look the same); and,

FIG. 3 is a bottom plan view.

The broken line and dotted lines are included for the purpose of illustration and form no part of the claimed design.

1 Claim, 3 Drawing Sheets

FIG. 1

FIG. 2

FIG. 3
